UNITED STATES PATENT OFFICE.

ANTHONY VASSELLI, OF NEWARK, NEW JERSEY, ASSIGNOR, BY MESNE ASSIGNMENTS, TO HARRIMAN NATIONAL BANK OF THE CITY OF NEW YORK, TRUSTEE.

TURNTABLE.

1,416,080.

Specification of Letters Patent. Patented May 16, 1922.

Application filed June 7, 1919. Serial No. 302,436.

To all whom it may concern:

Be it known that I, ANTHONY VASSELLI, a citizen of the United States, and a resident of the city of Newark, county of Essex, and 5 State of New Jersey, have invented a certain new and useful Improvement in Turntables, of which the following is a specification.

My invention relates to turn-tables for talking machines, and has for its objects to 10 provide such a structure which will be light in weight, strong and rugged in construction, cheap to manufacture, and more elastic in nature, whereby a cushioning effect will be produced.

15 A further object of the invention is to provide means of the character herein described, simple in construction, thoroughly reliable and efficient in its purpose and inexpensive to manufacture.

20 With these and other objects in view to be more fully set forth hereinafter, the invention consists in the novel construction, combination of elements, and arrangement of parts which will be exemplified in the 25 construction hereinafter described in the specification and illustrated in the accompanying drawings considered together or separately.

The invention will be first described in 30 connection with the accompanying drawings illustrating one embodiment of my invention, wherein similar reference characters are used to designate corresponding parts throughout the several views, and then more 35 specifically defined and indicated in the appended claims.

In the drawings,—

Fig. 1 is a bottom plan view of a turn-table embodying my invention; and

40 Fig. 2 is an enlarged sectional view on the line 2—2 of Fig. 1.

In carrying out my invention, I provide a base plate 1 of sheet metal, stamped or otherwise shaped to circular form, and having 45 a depending peripheral flange 2 and a depressed central portion 3, having a perforation 4. A fitting 5 is riveted to the under side of the base plate, and is provided with a cylindrical lug 6, which latter has a

50 tapered bore 7 for engagement with the turn-table shaft of a talking machine motor. The base is provided with a plurality of slots 8 arranged in circular form and spaced a short distance from the periphery of the 55 plate 1.

A supplemental disc 9 is carried on the base plate; said disc 9 may have a comparatively small perforation at its center through which the end of the turn-table spindle may project, but is preferably in the form of an 60 annulus, having quite a large central opening 10 as shown. The opening 10 in the plate 9 is preferably, but not necessarily of approximately the same diameter as the depressed portion 3 of the plate. 65

The disc 9 is provided with a plurality of preferably integral tongues 11 which may be struck from the plate. The number of tongues 11 corresponds to the number of slots 8. 70

A cover 12 preferably of plush or velvet is secured to one side of the disc 9, as by cement or in any suitable manner. The edge of the cover 12 is turned over the edge of the disc 9, as shown in Fig. 2. 75

The disc is now placed on the base plate with the covered side of the disc outward, and the turned over edge of the cover between the disc and base plate. The tongues 11 will extend through the slots 8, and are 80 bent upward against the under side of the base plate.

The disc 9 will not rest directly on the base plate, but will be separated therefrom by the thickness of the turned over portion 85 of the cover 12, whereby when pressure is applied to a record disc carried on the disc 9, the latter will have a cushioning or yielding effect, and thus prevent injury to the record groove by the reproducing stylus. 90

In accordance with the provisions of the patent statute, I have described the principle of my invention, together with the apparatus which I now consider to represent the best embodiment thereof, but I desire 95 it understood that my invention is not limited to the particular form of apparatus herein shown and described, as it is obvious that the particular embodiment herein shown and described is only illustrative of my invention, and that other means can be employed to obtain these objects and accomplish these results, without departing from the spirit of my invention. 100

Having now described my invention, what 105 I claim and desire to secure by Letters Patent is:

1. A turn-table, comprising a base plate, a disc carried by the plate, a yielding material interposed between the base plate and 110

disc, and means for holding the disc to the base plate.

2. A turn-table, comprising a base plate, a disc carried by the plate, a yielding material covering one side of the disc and extending between the plate and disc, and means for holding the disc to the base plate.

3. A turn-table, comprising a base plate, a disc carried by and spaced from the base plate, yielding means interposed between the said plate and disc and tongues integral with the disc and engaging the base plate for securing the disc to the base plate.

4. A turn-table, comprising a base plate, a disc carried by and spaced from the base plate, yielding means interposed between the said plate and disc the said base plate provided with a series of slots, and tongues carried by the disc and adapted to engage said slots to secure the disc to said base plate.

5. In a turn-table for talking machines, a disc, and a pad of yielding material fitted

upon said disc and having its outer edge turned over and under the peripheral edge 25 of said disc, the said disc having tongues adapted to engage the plate of the turn-table to secure the disc thereon with the inturned edge of the pad between the disc and plate.

6. In a turn-table including a base plate having a series of slots therein, a disc, and a pad of yielding material fitted upon said disc and having its outer edge turned over and under the peripheral edge of said disc, 35 the said disc having integral tongues adapted to engage the slots in said plate to secure the disc on said plate with the inturned edge of the pad between the disc and plate.

This specification signed and witnessed 40 this 2nd day of June, 1919.

ANTHONY VASSELLI.
